DOOR LOCK AND SAFETY LINKAGE UNIT

Charles H. MacMahon, Jr., Birmingham, Mich., assignor
to The Ducker-Singer Company, Birmingham, Mich.,
a corporation of Michigan

Application December 22, 1958, Serial No. 53,852

Term of patent 3½ years

(Cl. D50—7)

Fig. 1

Fig. 2

Fig. 3

Fig. 4

Fig. 5

Figure 1 is a perspective view of a door lock and safety linkage unit in closed position, showing my new design;

Figure 2 is a top plan view thereof;

Figure 3 is an elevational view of one end thereof;

Figure 4 is an elevational view of the other end thereof; and

Figure 5 is a perspective view illustrating the parts in extended position.

I claim:

The ornamental design for a door lock and safety linkage unit, as shown.
